**QUICK, DETACHABLE SAFETY SUPPORT
OR BELT**

John E. Berl, 5312 Kenilworth Ave., Baltimore, Md.
Continuation of application Ser. No. 28,962, May 13,
1960. This application July 27, 1962, Ser. No.
214,790

1 Claim. (Cl. 128—134)

This invention relates generally to safety harness, and more particularly it pertains to a means for restricting the movement of the extremities, wrists, ankles, and the torso of handicapped patients or persons without impairment to the circulatory system by pressure or physical discomfort. This application is a continuation of U.S. patent application, Serial No. 28,962, filed by applicant on May 13, 1960, for "Quick, Detachable Support or Belt," and now abandoned.

Strap-type supports are useful for guarding the safety of physically or mentally handicapped persons. In the past, leather or duck belting has been used on hospital beds, examination tables and wheelchairs to support a patient in a desired position. However, such belts leave much to be desired in comfort to the patient in cleanliness and compatibility with bed clothing and hospital type apparel.

It is, therefore, an object of this invention to provide a new and improved safety support which is padded, quilted, covered, and taped for comfortable wear and sanitation and which is easily adjusted and secured to the required length for the conditions under which it is to be used.

Another object of this invention is to provide an improved stitched composite cloth strap which is soft, which possesses a minimum of elongation under tension, and which launders well without creepage or balling.

Still another object of this invention is to provide a safety support which conforms to irregular surfaces under tension without undue strain on the stitching and which can be easily and economically manufactured in any desired length.

Another object of this invention is to provide a hospital safety belt assembly which features an easily removable friction buckle of improved holding quality especially compatible to the mechanical properties of a launderable fabric assembly.

To provide a buckle belt of improved construction and durability to withstand unpreceded extended usage under severe insalubrious environment, is still another object of this invention.

To provide a hospital belt of improved holding qualities which, in common with its buckle, is especially conforming to the rounded contour of body members of a patient, is a further object of the invention.

Yet another object of this invention is to provide a belt and buckle assembly which is less subject to contamination and more conducive to sterilization of all its parts than heretofore.

To provide a bed patient security harness which does not limit the patient's rotational mobility, thus preventing the formation of bed sores is another object of the invention.

And another object of this invention is to provide a universal service strap whose buckle can be positioned anywhere thereon and used singly or in together with another strap and the same or other buckles to fashion restrictive or positioning attitudes of the limbs or torso of living or dead creatures.

These and other objects and attendant advantages of this invention will become more readily apparent and understood from the accompanying specification and single sheet of drawings in which:

2

FIG. 1 is a perspective view of a safety support incorporating novel features of this invention;

FIG. 2 is a perspective view of a patient showing the safety support applied thereto;

FIG. 3 is an enlarged fragmentary elevation of safety support disclosing details of the construction thereof;

FIG. 4 is a fragmentary cross section taken on line 4—4 of FIG. 1 to disclose a manner of threading the strap ends of the safety support through a buckle therefor; and

FIG. 5 is a fragmentary cross section similar to that of FIG. 4 illustrating a preferred employment of the buckle.

Referring now to the details of the drawings, there is shown generally in FIG. 1 a safety support or belt 10. This safety support or belt 10 consists of composite stitched and taped fabrics having rounded ends 12 and 14 reeved through a readily detachable friction buckle 16.

As best illustrated in FIGS. 1 and 4, the buckle 16 consists of a pair of spaced parallel side legs 18, having a central leg 20 arranged parallel therewith but which is somewhat displaced from the common plane of the legs 18. The two ends 12 and 14 of the fabric belt 10 are threaded oppositely under the side legs 18 and over the central leg 20 with frictioned engagement under tension of the fabric ends 12 and 14 with the buckle 16 at the overlap providing a locking effect at any desired adjustment.

The buckle 16 may be used most effectively in an inverted position from that shown in FIG. 4. As illustrated in FIG. 5, the fabric of belt 10 is caused to bend more sharply with this employment of the buckle and consequently a greater frictional engagement is obtained between the overlapped belt ends.

The composite fabric of the belt 10 is made up of an inner woven cotton flannel 26, which is faced with outer cover cloths 22 and 24. It is important that the flannel 26 be oriented so that the strong warp threads thereof run lengthwise, with the relatively weaker "fuzzy" woof threads being placed or arranged substantially transversely of the belt 10. The flannel 26 and cover cloths 22 and 24 are secured together with spaced transverse stitching 28 at regular intervals (or irregular intervals, if desired) and with a plurality of rows of spaced and centered continuous longitudinal stitching 30 as shown best in FIG. 3.

The edges of the flannel 26 and cover cloths 22 and 24 are made co-extensive and are covered with a single continuous folded twill tape 32 positioned around the entire peripheral edge of the belt and secured by two rows of stitching 36 and 38 through all layers of the material.

The necessary splice in the tape 32 as shown by reference numeral 34 in FIG. 1 is made by overlapping the two ends so as to preserve the desired longitudinal tensile strength of the tape 32.

The improved safety support or belt 10 constructed as has been related is shown in use in FIG. 2 mounted around a patient positioned in a wheelchair. It will conform as smoothly and comfortably about the person as blanket material. In addition, the belt 10 can be used in conjunction with bed-ridden patients, or under other circumstances where it is desired to maintain a patient in a desired position. The safety belt or support 10 is especially adapted for handicapped patients, such as, but not limited to, paraplegics, paralytics, cerebral palsies, muscular dystrophy, geriatric, convalescing and aged persons. It can be utilized for numerous other purposes, such as examination tables.

The belt 10 is unyieldingly in tension and it presents a neat appearance consisting with hospital articles. The padding flannel 26 is adequately secured for long life under severe usage without danger of creeping, lumping up, or loss of resiliency even with repeated laundering.

The rough twill tape edge of the belt 10 is effective in

preventing slippage in the buckle 16 and provides further tensile strength in addition to that from the warp threads of the flannel 26.

Since the connection between the belt and buckle is of temporary nature and the buckle is readily removed only a relative small quantity of buckles will be required to be stocked despite a large number of belts in stand-by readiness. Moreover, the ready removal of the buckle facilitates the laundry processing of the belts and avoids damage to laundry machinery.

Obviously many other modifications and variations of the present invention are possible in light of the above teachings. It is, therefore, to be understood that within the scope of the appended claim the invention may be practiced otherwise than as specifically described.

What is claimed is:

A hospital retaining belt, comprising, a support strap consisting of an inner layer of woven cotton flannel, an outer layer of soft fabric material arranged on each side of said inner layer coextensive therewith, said inner layer and each said outer layer being elongated shaped and having coextensively arranged with each other a pair of ends and substantially parallel longitudinal edges, said inner layer and each said outer layer being secured to each other to form an assembly of layers by a plurality of spaced rows of stitching arranged transversely of said strap and a plurality of spaced rows of stitching arranged centered and lengthwise of said strap, the woven cotton flannel of said inner layer having its strong warp threads arranged lengthwise of said strap and its relatively weaker woof threads arranged transversely of said strap, and

rough twill binding tape arranged along the ends and edges of said assembly of layers and folded onto each side thereof, said binding tape being stitched to said assembly of layers adjacent the ends and edges thereof, thereby securing the ends and edges of said assembly of layers together and forming said strap, and a friction buckle consisting of a pair of parallel spaced side legs and an intermediate leg located therebetween and arranged parallel therewith but displaced laterally from the common plane of said side legs, the ends of said strap being inserted oppositely between said side legs and the intermediate leg of said buckle, said rough twill binding tape being in frictional engagement with said legs of said buckle and itself at the overlay of said strap within said buckle to obtain a locking effect between said strap and said buckle for any desired adjustment of said strap, whereby rotational movement by a patient retained by said belt is permitted to avoid bed sores and yet to maintain a safety support for said patient, said ends of said strap being free of engagement with said friction buckle, whereby said friction buckle is removable to enable said support strap to be laundered therewithout.
